UNITED STATES PATENT OFFICE.

JOSEPH P. GLASER, OF DETROIT, MICHIGAN, ASSIGNOR TO CHAMBERLIN METAL WEATHER STRIP CO., OF DETROIT, MICHIGAN, A CORPORATION OF MICHIGAN.

WEATHER STRIP.

Application filed April 1, 1922. Serial No. 548,589.

To all whom it may concern:

Be it known that I, JOSEPH P. GLASER, a citizen of the United States, residing at Detroit, county of Wayne, State of Michigan, have invented a certain new and useful Improvement in Weather Strips, and declare the following to be a full, clear, and exact description of the same, such as will enable others skilled in the art to which it pertains **10** to make and use the same, reference being had to the accompanying drawings, which form a part of this specification.

This invention relates to improvements in weather strips, and the object is to provide **15** a weather strip for use with sliding window sash or the like which consists of a body or base provided with a longitudinally extending sealing rib or flange for engaging a complementary groove with which the window **20** sash or like structure is provided. A feature of the invention is in the formation of the base or body of the weather strip with a shoulder adjacent one edge providing a guide for the positioning of the weather **25** strip in the channel of the window frame and thereby, without necessity of measurement, to position the sealing rib correctly relative to the groove of the sash. Ordinarily the sash to be used with a weather strip **30** of this character is provided with a groove by the sash manufacturer formed a certain distance from and parallel with the edge of the sash. With such weather strips heretofore in use and provided with a rib to engage **35** the groove of the sash, much care needs to be exercised in placing the weather strip in the frame in order that the rib will correspond in position with the groove of the sash. I have provided a shoulder or abutment at one edge of the strip which engages **40** against the parting strip and thus positions the rib to properly enter the sash groove and by this arrangement workmen can erect the structure at less expense than has heretofore been possible. Weather strips as heretofore used also have part of the base of the strip on one side of the sealing rib or flange corrugated longitudinally providing contact **45** surfaces engaged by the sash to reduce the frictional contact between the sash and the weather strip. While such arrangement is useful I have found that such former weather strips are not as fully effective in use as

is desired, and I have further found that by offsetting the base on one side of the sealing **55** rib with the upper surface in the same plane as the upper surface of the corrugations of the base on the opposite side of the sealing rib, possibility of flow of air between the sash and the strip is effectually prevented. **60** These several novel features and objects of the invention are hereinafter more fully described and claimed, and the preferred embodiment thereof is shown in the accompanying drawings in which— **65**

Fig. 1 is a cross sectional view showing a portion of a window frame and a sliding sash and the preferred form of my improved weather strip as applied thereto.

Fig. 2 is an enlarged end view of my improved weather strip. **70**

Fig. 3 is a perspective view thereof.

The window frame is indicated at 1. The usual parting strip is indicated at 2 and the usual moulding at 3 between which is a runway 4 or groove for the sash 5. The sash is provided with a longitudinal groove 6 and the weather strip 7 is preferably secured in the bottom of the runway 4. The strip is formed of sheet metal as is usual with this character of device and the body or base is provided with the usual parallel corrugations 8 extending longitudinally of the strip on one side of the flange or sealing rib 11 and this side of the strip may be nailed, as indicated at 9, to the frame. The corrugations 8 provide contact surfaces engaged by the sash and reduce the frictional contact of the sash with the strip to a minimum and further there is a half corrugation 10 at the **75** point of connection of the sealing flange or rib 11 with the body 7 of the weather strip which engages the edge of the groove 6 of the sash making a tight joint between that side of the sash and the weather strip having the corrugations 8. **80**

The sealing rib or flange 11 is formed by bending the strip upon itself intermediate and parallel with the edges in the form of a loop which is larger at the edge than at the **85** point of contact with the base, the two legs forming the rib preferably converging toward the base. The rib is thus sufficiently large at the point of bend to practically fill the groove and to prevent a flow of air **90** through the groove and the edge of the

groove contacts the longitudinal corrugation 10 to further effect a sealing of the space between the sash and the strip.

Strips have heretofore been made with the longitudinal corrugations and sealing rib, and a feature of this invention resides more particularly in the shape of the base on the side opposite that having the corrugations 8 and 10 and this is to provide an edge 12 to enter a groove formed in the parting strip and forming adjacent the edge 12 a shoulder 13 to provide an offset portion 14 of the base, the upper surface of which is in the same plane as the upper surface of the corrugations 8. This offset portion of the base thus contacts the edge of the sash for its full width.

With weather strips heretofore made, as above mentioned, there is more or less tendency for air to flow in the channels formed between the corrugations and the sash and to escape into the room past the moulding 3 which ordinarily is not very closely positioned to the sash. I avoid this defect by providing the offset portion 14 and shoulder 13. As will be readily understood the runway for the sash is usually of somewhat greater width than the sash and with weather strips heretofore made and provided with the sealing rib or flange, the position of the rib relative to the parting strip 2 could vary considerably and still allow the sash to be assembled at the frame. This left a space between the sash and parting strip and permitted air to pass into the room through the said channels and over the top of the inner sash of the window. By making the strip as disclosed herein, with the distance between the sealing rib 11 and the shoulder 13 practically equal to the distance from the side of the groove 6 of the sash to the face thereof adjacent the parting strip and by the shoulder 13 providing a guide so that the sealing rib is always readily set the required distance from the parting strip, I have provided a weather strip that secures an effectual sealing of the space between the sash and frame preventing a flow of air from the outside between the parting strip and sealing rib or into the channel between the part 15 of the sash and the weather strip as is possible with former constructions.

As above indicated, the function of the offset portion 14 is to provide a shoulder 13 with the projecting edge 12 from the said shoulder to ride in a saw kerf or groove in the parting strip. By such structure the workman, in assembling the strip in the frame, forces this edge 12 of the weather strip in the groove provided in the parting strip, the shoulder limiting the extent that the said edge may be inserted thereby correctly positioning the sealing rib to hold the sash to form a weather tight joint. It

will be understood that the runway for the sash is usually somewhat wider than the sash but, irrespective of the width of the runway, by my arrangement of the part 14 and shoulder 13 the sash is made to run properly in contact with the parting strip 2 and in sealed relation with the portion 14 and sealing rib 11 of the weather strip. The opposite edge of the weather strip, which is the edge to be nailed to the frame, may or may not extend fully to the inside moulding 3. The width of the weather strip is not material to this invention.

With my form of strip permitting accurate positioning of the rib as stated, a slightly greater surface of the weather strip is in contact with the edge of the sash than with devices heretofore used for this purpose as for instance the device as shown in the U. S. patent to H. E. Kenny, No. 786,972. With such former devices there is considerable space between the weather strip and sash along that edge of the sash between the sealing rib and parting strip of the frame. With my structure this space is sealed and, by raising the said part 14 of the base to the plane occupied by the contact surface of the corrugations 8, I have provided an effectual sealing of the space without any additional cost of manufacture of the weather strip and have secured the further advantage in that the strip is of less cost to erect as there is no necessity of the workman having to carefully measure the position of the rib relative to the stop or parting strip.

Having thus fully described my invention, what I claim is—

1. In combination with a grooved sash and its frame, a weather strip consisting of a base having a rib or flange extending longitudinally thereof and engaging in the groove of the sash, said base on one side of the rib having longitudinal corrugations, the opposite side of the base being offset with the surface thereof in the same plane as the surface of the said corrugations, the offset portion having a shoulder and an outwardly projecting edge in the same plane as the opposite side of the base, the side wall of the recess for the sash having a groove for the said edge of the strip substantially as and for the purpose described.

2. In combination with a grooved sash and a frame member having a runway or groove for the sash provided with side walls, a weather strip positioned in said runway comprising a base having an offset portion adjacent one edge providing a shoulder, there being a groove in the adjacent side wall of the runway into which the said edge may be inserted, a longitudinal rib on the strip engaging the groove of the sash, said offset portion extending from the said shoulder to the said rib, the remainder of the

base on the opposite side of the rib being positioned in the same plane as the first mentioned edge, and longitudinal corrugations in the said remaining portion of the base the inner face of which lies in the same plane as the inner face of the offset portion.

3. A sheet metal weather strip comprising a base member provided intermediate its edges with an integral rib or flange formed by folding the strip upon itself in a loop like form in cross section with the two sides of the base extending at right angles to the rib, one of said sides being flat and lying in a plane above that of the other side, said first side terminating in an edge portion occupying the same plane as the opposite side, a portion at a right angle to and connecting the edge and the main portion of the said first side providing an abutment.

20 4. A weather strip consisting of a piece of sheet metal folded upon itself in the form of a loop in cross section intermediate its edges and at practically a right angle to the sheet, the base on one side of the loop portion lying in a plane below that of the other side of the loop portion, the said last

side terminating in a shoulder with an outwardly projecting edge in the same plane as the opposite side of the base.

5. The combination with a window frame having a runway and a sash for movement longitudinally in the said runway and provided with a rib receiving groove, of a sheet metal weather strip having a base, one side of which lies in contact with the bottom of the runway and the other side of which is offset from the said base to contact with the adjacent edge of the sash, an outwardly extending rib member at the junction of the two sides of the base for engaging in the groove of the sash, one of the side walls of the said runway having a groove and the said side of the weather strip contracting the sash being formed with a shoulder and an outwardly projecting edge to engage the groove of the said side wall whereby the said side of the strip is held in position in the frame and the rib positioned at a predetermined distance from the said side wall.

In testimony whereof, I sign this specification.

JOSEPH P. GLASER.
